UNITED STATES PATENT OFFICE.

WILLIAM ROGERS, OF HARTFORD, ASSIGNOR TO SIMPSON, HALL, MILLER & CO., OF WALLINGFORD, CONNECTICUT.

DESIGN FOR A HANDLE FOR SPOONS AND FORKS.

SPECIFICATION forming part of Design No. 14,245, dated August 28, 1883.

Application filed July 13, 1883. Term of patent 7 years.

To all whom it may concern:

Be it known that I, WILLIAM ROGERS, a citizen of the United States, residing at Hartford, in the county of Hartford and State of Connecticut, have invented and produced a new and original Design for the Handles of Spoons, Forks, &c., of which the following is a specification, reference being had to the accompanying drawings, forming a part thereof, 10 in which is represented a front view of a spoon having my newly-designed handle.

The invention relates to a design for the handles of spoons, forks, and like articles of table-service; and it consists in the peculiar configuration of the upper part of the handle, in connection with circles inclosing rosettes embossed thereon, and also in a series of twin leaves strung together and arranged in three rows upon the handle-stem.

20 To describe the invention more fully, starting from the bowl of the spoon, or from the body of the article, the lower portion, A, of the stem of the handle has its sides slightly concave until the boss a is reached, and from 25 that point to the tip b the sides c c are straight

but divergent lines. Between these sides, and about one-third the distance between the boss a and tip b, there is a transverse panel containing three rosettes, d, inclosed in circles, and between these rosettes and the boss a there 30 is a panel, e, containing twin leaves strung together and arranged in three rows lengthwise of said panel. The tip b of the handle is formed with five scallops, each containing a circle, or scrolls resembling a circle, and each circle a rosette, b'. Immediately above the panel containing three rosettes, d, there is embossed upon the handle a central scroll and two half-scrolls, f, and similar scrolls, f', are embossed upon the handle-stem adjoining the bowl, and 40 between the scrolls f' and the boss a the stem is provided with a longitudinal row of twin leaves intermixed with small rosettes, all as shown in the accompanying illustration.

What I claim is—

The design herein-described and shown.
WILLIAM ROGERS.
